UNITED STATES PATENT OFFICE.

SAMUEL WARD GREENE, OF EAST GREENWICH, RHODE ISLAND.

DRINKING DEVICE.

1,079,596.

Specification of Letters Patent. Patented Nov. 25, 1913.

Application filed May 21, 1910. Serial No. 562,762.

To all whom it may concern:

Be it known that I, SAMUEL WARD GREENE, of East Greenwich, county of Kent, and State of Rhode Island, have invented 5 certain new and useful Improvements in Drinking Devices; and I do hereby declare the following specification, taken in connection with the accompanying drawings, forming a part of the same, to be a full, 10 clear, and exact description thereof.

The invention relates to an improved drinking device which is designed and adapted to take the place of the common drinking cups now in universal use in public places. It has long been recognized that 15 the use of the present public drinking cups is dangerous and has been the cause of the origination and spread of hundreds of cases of contagious diseases due to the contact of 20 the lips and breath of the user with the cup.

It is the object of the present invention to provide a drinking device in the use of which the lips and breath of the user are out of contact with any portion of the device 25 and which is therefore absolutely hygienic, as well as a device which is inexpensive to manufacture and simple in construction and operation.

To these ends the invention consists in the 30 novel construction, arrangement and combination of parts hereinafter fully described and particularly set forth in the claims.

In describing the invention in detail, reference will be made to the accompanying 35 drawings, in which—

Figure 1 is a side elevation of my novel drinking device in its preferred form and in operation. Fig. 2 is a vertical sectional view of the lower end of the delivery tube 40 on an enlarged scale showing the valve closed. Fig. 3 is a horizontal sectional view through the delivery nozzle on an enlarged scale. Fig. 4 is a detail. Fig. 5 is a side elevation of a modified form.

Referring to the drawings, the device 45 comprises a cup or fluid receptacle 1 provided with a downwardly extending delivery tube 2, and adjustably mounted upon a vertical bracket 3 secured to a side wall or 50 post 4 of a room or building. The cup 1 is held in adjusted position upon the bracket 3 by means of a clamp 5, and said bracket 3 is preferably provided with a scale 3' with 55 which an indicator 1' upon the cup 1 is adapted to coöperate to indicate proper adjustments.

Mounted in the side of a fitting 6 in the tube 2 near the bottom thereof is a delivery nozzle 7. The fitting 6 is provided with a transverse opening or passage 8 which communicates with the opening 7' in the delivery nozzle 7 and also with the interior of the delivery tube 2. Located in the opening 8 is a valve-stem 9 carrying a valve 10 which is normally held against the valve-seat 11 60 by means of a spring 12, one end of which bears against an annular shoulder 13 on the interior of the opening 8 and the other end of which bears against a nut 14 secured upon the end of the valve-stem 9, as shown 65 in Fig. 2.

The means for operating the valve 10 to open the same comprises a diaphragm 15 clamped between the fitting 6 and a coupling 16. The diaphragm 15 is operated by means 70 of a plunger 17, the upper end of which is slidably mounted in the coupling 16 and adapted to engage the diaphragm 15 and the lower end of which is slidably mounted in a plate 18 secured to the lower end of the delivery tube 2. The plate 18 is provided with a raised rim 19 to form a receptacle for any waste water that may leak from the nozzle 7 and is also provided with an opening 18' to permit such waste water to flow through 75 said plate and into a catch-basin 20. The plunger 17 is provided with a lateral extension 17' which extends through a longitudinal slot 21 in the delivery tube 2 and serves as means to limit the movement of the plunger 80 in each direction, as well as means for operating the valve 10 by hand when desired. The lower end of the plunger 17 is located above and adapted to be engaged by one end of a lever 22 pivoted to a projection 85 23 formed upon the underside of the plate 18. Adjustably mounted upon the other end of the lever 22 is a pin 24 which extends through an opening in the plate 18 and is provided upon its upper free end with a 90 chin-rest 25. Mounted upon the pin 24 is a guard or deflector 26 which is adapted to be normally held in front of the delivery nozzle 7.

Mounted above the cup 1 is a supply tank 105 27 provided with a delivery pipe 28 in which is a valve 29 adapted to be operated by a cord or chain 30 within easy reach of the user. Mounted upon the interior of the cup 1 is a float 31 which has an upright arm 110 32 bent over the top edge of said cup and carrying a tell-tale 33 to indicate the amount

of water within the cup 1 at all times. A series of pointed pins 34 are preferably secured in the delivery tube 2 around the nozzle 7 and extend out beyond the free end 5 thereof, so as to prevent a user from applying his lips to said nozzle.

The operation of the device is as follows: The valve 10 is normally held closed by the spring 12 and the chin-rest 25 and guard 26 10 are held in their raised positions by the lever 22. With said parts in this position the user pulls down the cord 30 to open the valve 29 and permit water to flow from the supply tank 27 into the cup 1 and fill or 15 partly fill the same, as desired, the amount of water entering the cup being indicated by the tell-tale 33. The user now rests his chin upon the chin-rest 25 with his mouth closed. As the mouth is opened the chin-rest 20 25 is depressed, thereby moving the guard 26 down away from the delivery nozzle 7 and raising the plunger 17 up against the diaphragm 15. As the valve 10 opens, the water from the cup 1 will flow through 25 the opening 8 and out of the delivery nozzle 7 into the open mouth of the user, as shown in Fig. 1. Upon the mouth receiving a sufficient quantity of water for swallowing, the user by closing his mouth to swallow will 30 remove the pressure of his chin upon the chin-rest 25 and thereby allow the spring 12 to automatically close the valve 10 and shut off the flow of water. By continuing the 35 operation of opening and closing the mouth while the chin is resting upon the chin-rest 25 the water will continue to be intermittently supplied to the user until he has received the desired amount.

If it is desired to regulate the position of 40 the chin-rest to accommodate persons of varying height, the cup 1 may be raised or lowered upon the bracket 3 and held in adjusted position by means of the clamp 5. It will of course be understood that the adjustment of the cup 1 on the bracket 3 likewise 45 adjusts the height of the chin-rest 25. If only a slight adjustment of the chin-rest 25 is desired it can be effected by means of the nut 24' upon the pin 24.

If there should happen to be some water 50 left standing in the cup 1 when it is desired to use the device, the user simply raises the plunger 17 by hand by means of the lateral projection 17', thereby opening the valve 55 10 and emptying the cup 1. It will be seen that when the plunger 17 is thus moved by means of the projection 17' the guard 26 is not moved and the water flowing out of the delivery nozzle 7 will strike against said 60 guard and be deflected on to the plate 18 adjacent the opening 18'.

Fig. 5 shows a modified form of the device showing the same in portable form and adapted for hand use as an ordinary drinking cup. In this construction the plate 18

forms the top of a receptacle 35 which is provided with a bottom 36 and serves as a catch basin for receiving and holding the waste water. The bottom 36 is provided with an outlet 37 for emptying the contents when desired and also with suitable legs or standards 38 for supporting the device. Said Fig. 5 also shows the normal position of the chin-rest 25, guard 26 and lever 22, and it will be seen that the lever 22 is normally out of contact with the plunger 17. This is to allow for a sufficient depression of the chin-rest 25 to permit the mouth to be partly opened and the guard 26 removed from in front of the delivery nozzle 7 before the plunger 17 is raised to open the valve 10. 70 75 80

What I claim as my invention and desire to secure by Letters Patent is:

1. In a device of the character described, the combination, with a fluid receptacle, of a delivery nozzle, a valve, and means adapted to be operated by the opening and closing of the mouth for operating said valve. 85

2. In a device of the character described, the combination, with a fluid receptacle, of a delivery nozzle, a waste water receptacle below said delivery nozzle, and means for deflecting the water from said nozzle to said waste receptacle arranged and adapted to be moved in front of and away from said 90 delivery nozzle. 95

3. In a device of the character described, the combination of a fluid receptacle provided with a horizontal outlet and means for positioning the mouth at the proper height 100 to receive water from said outlet. 100

4. In a device of the character described, the combination, with a fluid receptacle, of an outlet, a valve for controlling the flow of fluid through said outlet, a depressible chin-rest adapted to operate said valve and to hold the mouth in position to receive fluid flowing from said outlet, and means for adjusting the height of said chin-rest. 105

5. In a device of the character described, the combination, with a fluid receptacle, of an outlet, a valve controlling said outlet, a depressible chin-rest, and means for operating said valve when said chin-rest is depressed a predetermined distance. 110

6. In a device of the character described, the combination, with a fluid receptacle, of an outlet, a guard normally held in front of said outlet, and means operated by the opening of the mouth for moving said guard away from said outlet. 115 120

7. In a device of the character described, the combination of a fluid-receptacle, means for adjusting the height of said fluid-receptacle, and chin-operated means for drawing fluid from said receptacle. 125

8. In a device of the character described, the combination, with a fluid receptacle, of a delivery nozzle, a valve controlling the flow of fluid through said nozzle, a spring 130

normally holding said valve closed, a chin-rest adjacent said nozzle, a lever adapted to be operated by said chin-rest, and a plunger adapted to be operated by said lever to open 5 said valve, said lever and plunger being normally out of engagement with each other.

9. In a device of the character described, the combination, with a fluid receptacle, of 10 a delivery tube having a fitting provided with a delivery nozzle, a transverse opening and a valve-seat, a spring actuated valve-stem mounted in said transverse opening and provided with a valve normally 15 held against said valve-seat, a diaphragm clamped between said fitting and a coupling in said delivery tube and underlying said valve-stem, a plate secured to the end of said delivery tube, a plunger slidably 20 mounted in said coupling and plate directly beneath the diaphragm, and a lever pivoted to said plate and having one end underlying said plunger and the other end provided with a chin-rest.

25 10. In a device of the character described, the combination, with a fluid receptacle, of a delivery nozzle, a valve normally closed for controlling the flow of fluid through 30 said nozzle, a guard normally held in position in front of said delivery nozzle, and means for moving said guard away from the delivery nozzle, and means for opening the valve after said guard has been so moved.

35 11. In a device of the character described, the combination, with a fluid receptacle, of a delivery nozzle, a valve normally closed for controlling the flow of fluid through 40 said nozzle, chin-operated means and hand-operated means for opening said valve.

12. In a device of the character described, the combination, with a fluid receptacle, of a delivery nozzle, a valve normally closing 45 said nozzle, a guard in front of said nozzle, chin-operated means for opening said valve and removing said guard from in front of said nozzle and hand-operated

means for opening said valve without removing the guard from in front of said nozzle.

50

13. In a device of the character described, the combination, with a fluid receptacle, of a delivery tube provided with a delivery nozzle and a valve for controlling the flow of fluid through said delivery nozzle, chin-operated means for operating said valve, and a plate secured to the end of said delivery tube and provided with a raised rim and an outlet opening.

55

14. In a device of the character described, the combination, with a fluid receptacle, of a horizontal delivery nozzle, a valve controlling the flow of fluid through said delivery nozzle, chin-operated means for operating said valve, and means to prevent access 60 of the lips to said delivery nozzle.

65

15. In a device of the character described, the combination, with a suitable bracket, of a fluid receptacle adjustably mounted thereon, means for clamping said fluid receptacle in position on said bracket, means for supplying said fluid receptacle with fluid, and chin-operated means for drawing the fluid from said receptacle.

70

16. In a device of the character described, the combination, with a suitable bracket provided with a scale, of a fluid receptacle adjustably mounted on said bracket and provided with an indicator arranged to register with said scale, means for locking 75 said fluid receptacle in adjusted position, hand-operated means for supplying said fluid receptacle with fluid, means for indicating the amount of fluid in said receptacle, chin-operated means for drawing 80 fluid from said fluid receptacle, a waste receptacle, and means for directing waste water from said fluid receptacle to said waste receptacle.
